UNITED STATES PATENT OFFICE.

WILLIAM SPAIN, OF ST. LOUIS, MISSOURI, ASSIGNOR TO CORN PRODUCTS REFINING COMPANY, OF NEW YORK, N. Y., A CORPORATION OF NEW JERSEY.

CAN-FEEDER.

944,828.

Specification of Letters Patent. Patented Dec. 28, 1909.

Application filed October 26, 1908. Serial No. 459,637.

To all whom it may concern:

Be it known that I, WILLIAM SPAIN, citizen of the United States, residing at St. Louis, State of Missouri, have invented a certain new and useful Improvement in Can-Feeders, of which the following is a full, clear, concise, and exact description, reference being had to the accompanying drawings, forming a part of this specification.

My invention relates to can feeding machines and has for its general object the provision of mechanism which will automatically dispose cans, pails, or other receptacles in uniform position and transfer them while such position is maintained, for whatever subsequent treatment may be desired, in predetermined presentation.

The device of my invention is especially adapted for use in combination with labeling mechanism and I have therefore illustrated it as so applied, though it is evident that my invention is not only adapted to this association, but is also capable of other uses and other association.

The nature of my invention will be well understood by a description of the preferred embodiment thereof shown in the accompanying drawings, in which—

Figures 1 and 1^a, appearing upon different sheets of the drawings, when placed end to end along the vertical dash lines, together constitute a side central elevation of the machine on line *a* or Fig. 2, certain structural parts not being illustrated in order that important characteristics of construction may more clearly appear. Fig. 2 is a view partly in cross-section and partly in end elevation, of the structure as it appears in Figs. 1 and 1^a. Like parts are indicated by similar characters of reference throughout the different figures.

The cans, having the bail-receiving ears 1—1, are placed at random upon the receiving ends of the track rails 2—2, beneath which are mounted the clock-wise rotating sprocket wheels 3—4 in engagement with a sprocket chain or belt 5 that is driven by one of the sprocket wheels. Fingers 6 are provided at regular intervals along the sprocket chain or belt, the space between adjacent fingers being considerably in excess of the diameter of a can. The upper stretch of the sprocket chain preferably does not rise above the upper surface of the rail or

track structure 2, but the fingers 6 carried on the upper stretch of said sprocket chain are adapted to project considerably above said track structure. The chain 5 is disposed between the rails 2—2 and in a vertical plane parallel therewith, whereby said fingers, in rounding the sprocket wheel 3, are gradually projected to their full extent above said rails, whereby the cans (which are loaded at random upon the tracks in advance of the rising fingers) are engaged by said fingers and moved along the track toward the labeling mechanism.

In order that similar parts of the cans may be initially presented to the labeling mechanism, the cans are caused to slide along the rails 2—2 during a part of the travel of the cans toward the labeling mechanism and in order to prevent the cans from rolling upon their ears during the time that the cans are to slide on the rails 2—2, I locate two guard rails 7—7 above the rails 2—2, the rails of the guard structure 7 however being preferably slightly closer together than the rails 2—2 to accommodate other mechanism to be described. The guard rails 7 are but a fraction of the length of the rails 2, as their function is simply to insure the proper location of the cans upon the tracks 2—2 during the time that said cans are to slide upon said tracks, mechanism being provided for rolling the cans upon the tracks 2 after the cans have passed the guard rails which take part in properly presenting the cans to the mechanism that effects the rotation of the cans on the tracks toward the labeling mechanism. The vertical space between the rails 2 and 7 is just enough in excess of the can diameter to afford clearance between the upper rails and the sliding cans, the rails 2 and 7 being sufficiently close together to prevent the cans from rising upon their lower ears. From the illustration it will be observed that any rotating tendency imparted to the cans is not only resisted by the lower ears of the cans coming in contact with a lower rail 2, but also by the upper ears coming in contact with an upper rail 7, the diameters of the cans passing through the can ears being rearwardly inclined while the cans are passing between the guarding devices 2 and 7.

The distance over which the cans are caused to slide is sufficient in extent to insure similar positions of the cans when they

leave the guard rails 7, the cans after leaving the guard rails being engaged by the feeding belts 8 that are pressed into engagement with the cans by well-known tension mechanism, said feeding belts not only serving properly to roll the cans upon the tracks 2—2 so as to bring said pails properly into contact with the pasting mechanism and the label box, but said belts also serving to discharge the labeled cans from the machine.

In order to prevent the cans from rising upon their ears as they are rolled upon the tracks 2, said tracks serve to permit the cans themselves to roll smoothly thereupon.

15 While the lugs or ears of the receptacle have been illustrated and described as a convenient agent for contacting with the guide and arresting rotation, other projections on the receptacles may be employed in like 20 manner for this purpose.

By the term "can" as used in the specification and claims, I intend to include generally any receptacles adapted to be fed as described, irrespective of whether they be 25 commonly designated as cans, pails, or by other names.

While I have herein shown and particularly described the preferred embodiment of my invention, I do not wish to be limited 30 to the details of construction shown, but

Having thus described my invention, I claim as new and desire to secure by Letters Patent the following:—

1. A can feeder including a track structure upon which the cans may initially roll and thereafter slide to peripherally adjust the cans with relation to the track structure, means operating upon the cans to prevent the rotation thereof while sliding, and means 35 for advancing the cans upon the track structure upon the separation of the cans from the aforesaid means.

2. A can feeder including a track structure upon which cans may initially roll and thereafter slide to peripherally adjust the cans with relation to the track structure, a 40

guard structure coextensive with a portion of the track structure and serving to prevent rotation of said cans while sliding, and means for advancing the cans upon the track 50 structure upon the dissociation of said cans from said guard structure.

3. A can feeder including a track structure upon which the cans may be slid during a part of their travel, means operating upon the cans to prevent rotation thereof while sliding to peripherally adjust the cans with relation to the track structure, and means acting positively to transfer the cans upon the dissociation of the cans from the afore- 60 said means.

4. A can feeder including a track structure upon which cans may be slid during a part of their travel, a guard structure coextensive with a portion of the track structure 65 and serving to prevent rotation of said cans while sliding to peripherally adjust the cans with relation to the track structure, and means acting positively to transfer the cans upon the dissociation of the cans from the 70 guard structure.

5. A can feeder including a track structure upon which cans may be placed and slid, and means for holding the cans from rotation while sliding to peripherally adjust 75 the cans with relation to the track structure.

6. A can feeder having a track structure upon which cans may initially roll and thereafter slide, and means for arresting the rotation of successive cans in uniform position and maintaining this position in a subsequent sliding movement to peripherally adjust the cans with relation to the track 80 structure.

In witness whereof, I hereunto subscribe my name this 23rd day of October A. D., 1908.

WILLIAM SPAIN.
